CODE CONVERTER

James A. Spencer, Teaneck, N. J., assignor to
Radio Corporation of America, a corporation of
Delaware

Application August 26, 1939, Serial No. 292,051

23 Claims. (Cl. 178—17)

This invention relates to wire and wireless telegraphy.

An object of the invention is to provide automatic mechanism for changing signals from one 5 code to another code.

Another object is to automatically change signals from a single-case code to a double-case code, that is, upper and lower case.

A further object is to provide means for automatically changing signal of unequal length code 10 to signals of equal length code.

More specifically, it is an object of the invention to provide means for automatically changing signals from cable code to Baudot code.

Additional objects will appear in the following 15 description, reference being had to the drawings in which:

Fig. 1 is a front elevation of the code converter, certain parts being broken away to better illustrate the mechanism.

Fig. 2 is a rear elevation of the code converter, certain parts being omitted to simplify the illustration.

Fig. 3 is an end view of the converter.

Fig. 4 is a top view of the converter, certain parts being omitted.

Fig. 5 is a section of the mechanism for shifting the Creed code bars, taken along the lines 5—5 of Fig. 4.

Fig. 6 is a section taken on the lines 6—6 of Fig. 5.

Fig. 7 is a detail section of the switch operated by the shift mechanism.

Fig. 8 is a section showing the details for making an indication upon failure of the selection mechanism to operate.

Fig. 9 is a section taken along the line 9—9 of Fig. 5 showing the details of the spacing comb at either end of the cable code bar assembly.

Fig. 10 is a fragmentary perspective view of the operating mechanism of the converter.

Fig. 11 is a diagrammatic top view of the cable selector bars and the Baudot selector bars showing the relative position of the slots in respect 45 to the cross bars.

Fig. 12 is a diagram of the electrical circuit of the code converter.

Fig. 13 is a view of a section of tape containing perforations for cable code characters.

Fig. 14 is a front view of the shift bars.

Fig. 15 is an end view of the shift bars shown in Fig. 14.

Referring more particularly to Figs. 1 and 2, the code converting apparatus is mounted on plate 55 10. The selector head of the well known Creed

printer is mounted on the base 11. It consists of an operating cam generally designated as 12 (see also Figs. 3 and 10) for producing the desired selection movements. A motor, not shown, operates the cam shaft 12' and other movable parts through shaft 12a and spiral gears 12b and 12c. The Creed selector head contains a tape operating toothed wheel 13 fitting in the center holes of tape 14 positioned above a tape-track 15, omitted in Fig. 10. Beneath this tape-track is 10 positioned twenty pecker bars arranged in pairs, one pair, 16, 17 being shown in Figs. 1 and 10 the others being omitted.

All of the pecker bars are moved against the perforated tape by springs 18 shown in Fig. 1, 15 when lever 19 moves pin 20 by engagement of roller 21 with cam 22. The toothed tape wheel 13 is moved counter-clockwise, as shown in Fig. 10, by means of a rack 13', link 23, arm 24, arm 25, arm 26, roller 27 and cam slot 28. The arm 24 is 20 positively moved to the right by arm 25 but in the reverse direction it is yieldingly moved to the left by spring 29, arm 24 being pivoted to the arm 25 at 30.

The rack 13' operates the toothed wheel 13 25 through gear 32 when the arm 20 moves to the right in Fig. 10 but not when it moves to the left. This is accomplished by link 33 and bell crank lever 34 through engagement of roller 35 with cam surface 36, the bell crank being pivoted at the 30 point 37. The arm 38 of this bell crank lever has an extension 39 secured thereto, as shown in Fig. 1 and Fig. 2, but omitted from Fig. 10 for clarity of illustration. The purpose of this extension 39 is to render the tape feed inoperative during the 35 shift from upper to lower case and vice versa, and it will be referred to later in detail.

Since the number of elements in each cable code character is variable, the tape 14 must be moved varying distances after each code character is 40 transmitted. For example, in the transmitting position, the first and fourth pecker bars will rise for letter A. In such position, the second, third, fifth, and seventh will rise for the letter B. Similarly the second, third, sixth and seventh will rise 45 for the letter C. This will be apparent from inspection of the section of the perforated tape 14 shown in Fig. 13, where perforations above the center line of driving holes represent dots and perforations below such line represent dashes. 50 In between the characters there are no code perforations. Hence, the first pair of pecker bars after each code character cannot rise.

To permit the feeding of the tape the varying distances required for the code characters, lever 55

40 is moved upwards whenever any lever of each pair of levers, for example, 16 and 17, is elevated, by springs 18 (Fig. 1). This arm is pivoted at 41 and has arm 42 extending into the path of rack 13'. Arm 40 is maintained in engagement with abutments 43, on the arms 16, 17, by spring 44 (Fig. 1).

When the perforated tape contains perforations for the letter A, for example, adjacent the wheel 13, arm 40 connected to the first two pairs of pecker levers will rise (see Fig. 13) because one pecker bar in each pair will, due to the perforations, rise. This will throw the arms 42 corresponding to the first two pecker bars out of the path of the rack 13', but the arms 40 for pecker bars at the third center perforation in Fig. 13 will not rise, as there are no code perforations at this point. Consequently, when the rack moves to the left in lowered position it can move the distance of two center holes only, the pivot 30 and spring connection 29 permitting this reduced movement. In the return movement to the right the rack will rise and feed the tape two perforations only when arm 25 engages arm 30.

If the letter B is the code character nearest the toothed wheel 13, levers 40 will rise and remove the arms 42 out of the path of the rack 13' corresponding to the first four pairs of pecker bars. The levers 40 corresponding to the fifth pair of pecker bars, which are positioned at the driving hole for the space following the letter B will not rise. Therefore, the associated arm 42 will serve as an abutment to stop the rack in its movement to the left in lowered position. When the rack rises and returns to the right it therefore will move the tape the distance corresponding to five feed holes or the length of the code for letter B.

In the way described the tape is moved the correct amount for the transmitted character which always is the character nearest to the toothed wheel 13. While the pecker bars for succeeding characters rise throughout the remainder of the racetrack to the left in Fig. 10, in accordance with the succession of code characters in the message no signals are transmitting for them because of non-alignment of slots in the selector bars, as will be later apparent.

Whenever any pecker bar rises due to the presence of a code perforation in tape 14, it operates one of the levers 45 by means of lugs 46, 47, on each pecker bar between which the reduced ends slide freely in a longitudinal direction. Whenever a lever 45 is operated, the left-hand end (in Fig. 10) drops down into position to engage its corresponding lever arm 48, two only being shown. In the disclosed embodiment I have provided for use of only fourteen of the twenty levers of the Creed selector head which with cooperating mechanism enables one to use a code of twenty-six alphabetical characters, the numerical characters and nine additional characters, as shown at the top of Fig. 11.

Accordingly there are only fourteen lever arms 48. Levers 45 are pivoted at 49 on frame 50 which itself is pivoted at 51. Spring 52 resiliently urges frame 50 and levers 45 to the left in Fig. 10, but the frame is prevented from moving, except in proper timed relation, by cam 53 on cam shaft 12'.

To permit the selector levers 45 to bring about the operation of the proper contact levers in the Baudot code apparatus, the lever arms 48 project into slots 54 in selector bars 55 mounted in a raceway 56, there being one selector bar for each lever arm 48. Consequently in the embodiment dis-

closed there are fourteen of these bars 55. There are no such lever arms and bars for the last six levers of the standard Creed selector head. Obviously these could be provided for the remaining six selector levers in apparatus designed for use of the entire cable code combination whenever desired.

By referring particularly to Fig. 5, it will be seen that the levers 48 are pivoted at 57 in frame members 58 secured to the sides of the raceway 56, as indicated in Figs. 5 and 6, particularly.

It is preferable to separate each lever 48 from its adjoining levers and therefore I provide a comb arrangement consisting of a plate 59, having thin spaced plates 60 soldered or otherwise fastened in slots therein. These plates 60 extend into thin milled slots 61 in the raceway 56. For clarity of illustration the thin plates 60 are shown as lines having no thickness capable of being sectioned. Each of the cable code selector bars 55 is preferably likewise separated from its neighbors by a comb arrangement at each end of the raceway 56. This comb consists of a plate 62 in which are soldered or otherwise fastened thin plates 63, as shown in Fig. 9. These thin plates 63 extend into milled slots 64 in the raceway 56 (Fig. 4). Narrow transverse bars 65 may be placed at each end and at the middle of the raceway 56 to lessen friction in the movement of bars 55. A series of transverse levers 66 are pivoted on a rod 67 extending through a hole 68 of each (Figs. 1 and 10). At the rear of the code converter, as shown in Fig. 2, the levers 66 are properly spaced by bushings 69 of the required thickness. The rod 67 is secured in the end plates 70, 71 and center plate 72. All of these plates act as frame members for the converter and are rigidly fastened to the bottom plate 10 by screws or other fastening means not shown.

For proper spacing of the cross levers 66 at the front part of the converter, as shown in Fig. 1, a slotted side plate 73 is fastened to the end plates 70 and 71. The spaces between the slots in the plate 73 will be the same as the thickness of the corresponding bushings 69 shown at the rear in Fig. 2. The center plate 72 may be slotted, as indicated at 74, for one of the cross bars 66. This center plate decreases in height and is fore-shortened, as shown by the dotted line 72' and 72'' in Fig. 3 so as to pass under the raceway 56 and provide room for parts to be later referred to.

Each transverse lever 66 has a hole or other means 75 for securing a spring 76 for biasing it downwards. The other end of the spring is fastened in holes 77 or other means in a member 78 fastened to the base plate 10 (Figs. 1 and 3).

In Fig. 1 only seven of the springs 76 are shown so that other devices will not be obscured but it will be understood that each cross lever 66 has a tensioning spring 76. In Fig. 1 parts of the plate 73 and member 78 are broken away to illustrate parts that otherwise would be hidden from view.

For rigidly holding the end plates 70 and 71 and center plate 72 together, a cross member 79 is fastened thereto (Fig. 3). This cross member, springs 76 and member 78 are omitted from Fig. 2 for clarity of illustration.

Five slotted Baudot code bars 80, 81, 82, 83, 84, extend across the code converter and are positioned in slots in the end plates 70, 71 (see particularly Fig. 4). End plates 70 and 71 have a projection or enlargement 85, 86, at the top front for formation of the slots for accommodating these Baudot code bars. Also positioned in slots 75

in this enlargement are shift bars 87, 88, which provide for shifting from upper case to lower case or vice versa. These shift bars are required in making the code conversion because, as is well known, the cable code is a single case code whereas the Baudot code is a double case code.

Each of the Baudot code bars 80 to 84 rest on bell crank levers 89, 90 (Figs. 1 and 10). These bell crank levers are pivoted at 91, 92, by small shafts extending from ears 93, 94, on the slotted bar 13, to similar ears 95, 96, on raceway 56 (Figs. 1, 5 and 8) but they may be pivoted in parts secured in any other way.

The cable code bars 55 are slotted to permit one of the cross levers 66 to drop into aligned slots, there being in such position one or more ridges under all of the other bars to prevent their dropping at such time. The Baudot code bars are also slotted so that the proper ones will be lowered by the cross levers, as later described.

As is known, some of the characters of the cable code contain other code characters. For example, the letter A, consisting of a dot and a dash is contained in the letter J, which consists of a dot and three dashes. Consequently, if no provision were made for preventing it, when code character J is transmitted, code character A would also be transmitted. The code character A is also contained in seven other code characters. Twenty-two other code characters also are contained in one or more other code characters, some of them, as E or T, twenty or more times. Multiple action in case of such characters is prevented by slotting the code bars so that when the cross lever for the longer of the code characters is operated by the aligned slots, there will be at least one ridge under the cross lever of the other character so that it cannot drop. Special care has to be taken in slotting the code bars in this respect because the Creed selector head sets up a combination in the raceway for several characters simultaneously and if the movement of the bars is impeded, jamming would result. For example, the letter E following the letter T or vice versa, would cause jamming of the code bars 55 if they were slotted without giving consideration to this matter. It is therefore necessary to permit movement of other bars 55 other than those of the transmitted code character.

In Fig. 11 I have shown how the cable and Baudot code bars may be slotted to permit transmission of proper code characters without causing the cross lever or any other character to drop and without causing any cable code bars to jam but this does not preclude the possibility of a different system of slots for correct operation. In this figure the forty-five cross levers 66 are not given a material thickness as it would complicate the illustration. Each cross bar is shown as a line. The cable and Baudot code bars are not separated from each other according to actual scale because this figure is diagrammatic to illustrate only the relation of the slots and ridges to the cross levers, the ridges being indicated by heavy solid lines and the slots by spaces.

To indicate a failure of the cable code selector head to respond to a signal, I have provided an extra cable code bar 97 (Figs. 8 and 10) in raceway 56. This extra code bar is so slotted that it normally presents a ridge 97' to each cross lever except the last one designated as 66a. Under this cross lever a slot is normally presented. When the extra code selector bar 97 is moved to the left, by means later described, a slot is pre-

sented under all of the cross lever 66 and a ridge 97" is presented under cross lever 66a (Fig. 11). Thus when any one of the cross levers 66 drops, due to aligned slots in the code bars 55 and 87, the latter is held from return movement to the right, but if none of the bars 86 operate, the extra bar 97 returns to the right and the mis-selection cross lever 66a drops into the slot adjacent ridge 97" which causes an indication of the mis-selection, as will later be described in detail.

The cam shaft 12' (Figs. 1 and 2) has a spiral gear 98 meshing with a spiral gear 99 keyed to cross shaft 100. This cross shaft is journaled in bearings 101, 102 and center plate 72 which are secured to the base plate 10. The end plates 70 and 71 have vertical slits 103 extending over the shaft 100 (Fig. 3) though these end plates could be used as bearings if desired.

Shaft 100 has a thrust bearing 104 for taking care of the thrust produced by the spiral gears. Also, the bearing 101 may contain a thrust bearing.

The shaft 100 has two gears 105 keyed thereto which mesh with gears 106 fastened on a shaft 107 journaled in the end plates 70, 71, and center plate 72 (Fig. 4). Shaft 107 has at each end and in the center a cam 108 (Fig. 8) for timed movement of operating cross bar 109 that holds the cross levers 66 and 66a in proper elevated position and permits the selected one of such levers to lower into the slots of the selector bars 55 in proper timed relation (Fig. 10). The cross bar is part of a bail and is secured to members 110 fastened to rod 111 journaled in plates 70, 71 and 72. These members 110 have cam followers 112, rollers being shown, which engage cams 108 to produce the timed release of cross levers 66.

Shaft 107 has an extension 113 on which is keyed disc 114 having a cam 115 engaged by a cam follower 116 on lever 117, the latter being pivoted at 118 (Figs. 2, 3 and 8). The upper end of lever 117 is pivoted at 119 to the mis-selection code bar 97 for producing the timed movement of that bar when a cross lever 66 fails to operate, as previously referred to. The cams 108 and 115 are so positioned in respect to their cam followers that the cross bar 109 is lowered to permit operation of the selected cross lever 66 slightly prior to the release of follower 116 from cam 115.

Power shaft 120 has spiral gears 121, 121, meshing with spiral gears 122, 123, keyed to shafts 124, 125, respectively Fig. 2. Shaft 125 is the usual shaft of a teletypewriter transmitter 126 well known in the art. This transmitter in addition to a start-stop cam (not shown) contains five switch operating cams 127, only one of which is visible in Fig. 1. Referring particularly to Fig. 2, each cam operates a cam follower 128 by cam detent 129. The cam follower 128 is mounted on a bell crank switch lever 130. The switch 131 controlled by switch lever 130 is maintained in open position except when cam 127 presents cam slot 129 thereto, providing that catch 132 on pivoted lever 133 has been removed from engagement with the bell crank. Lever 133 extends into slot 134 in bar 135. A pivoted clip 136 at each side retains the end of the lever 133 in the slot when in proper position, the clips 136 being moved aside to permit the lever and slot to be shown. Bars 135, of which there are five, are pivoted in bell cranks 89 and 90 which are connected to the Baudot code bars 80 to 85, as pre-

viously described. It will thus be seen that each of the five code bars 80 to 85 controls its individual switch 131 on the teletypewriter transmitter in the same way that such switches are controlled by the usual typewriter keys of the teletypewriter transmitter as normally constituted. Reference character 137 indicates the well known locking-loop on the teletype transmitter for prevention of movement of levers 130 after the selection has been made, which is well understood in the art.

Shaft 124 operates the teletypewriter transmitter 138 which contains cams and switches similar to the teletypewriter transmitter 126. Parts in transmitter 138 that are similar to those of transmitter 126 have been given the same reference characters and description of these similar parts is not required. Transmitter 138 unlike transmitter 126 has a locking lever 133 for only one of the five switch levers 130 and this one is associated with No. 3 switch lever. Transmitter 126 sends out the Baudot pulses, both upper and lower case, for operating selector mechanism of the teletypewriter printer at the receiver and transmitter 138 produces the signal for shifting the printer mechanism from upper to lower case and vice versa.

When locking lever 133 is disengaged from bell crank lever 130 the five bell crank levers of transmitter 138 are free to move and signal pulses one, two, three, four and five are sent out in one revolution of shaft 124. This is the signal to the receiver for the automatic shifting of the printer from upper to lower case. When locking lever 133 is in engagement with the third bell crank 130 the third switch 131 cannot close during the revolution of shaft 125 and during such revolution signal pulses one, two, four and five only, are transmitted. This produces the signal at the receiver for shifting from lower case to upper case.

The locking lever 133 for producing the shift from upper to lower case is pivoted in projection 140 by a slot arrangement similar to that already described in connection with locking lever 133 for transmitter 126. Projection 140 is secured to a cross bar 141 (Figs. 7 and 14). Bar 141 is pivoted to double bell crank levers 142, 143. The arms 144 and 145 of the double bell crank lever support shift bar 87 (Figs. 4, 14 and 15). The arms 146 and 147 of the double bell crank levers support shift bar 88.

When the position is as shown in Fig. 14 and any one of the upper case transverse levers 66 is operated, one only of these being shown, shift bar will be lowered and shift bar 88 will be raised. This will move bar 141 to the left and move locking lever 133 into position to prevent the movement of the third bell crank lever 130 when cam slot 129 is opposite cam follower 128. Therefore, when shift bar 87 is lowered by the operation of an upper case cross lever 66, the third pulse cannot be sent out from transmitter 138, but only pulses one, two, four and five. As is well known, this is the signal for producing a shift to upper case at the printer.

Whenever a lower case lever 66 (one only being shown in Fig. 14) is lowered by the selecting mechanism shift bar 88 will be lowered and shift bar 87 will be raised. The position will be as then indicated in Fig. 14. This action moves bar 141 to the right and moves locking lever 133 away from locking position in respect to the third switch lever. During the next rotation of shaft 125 signal pulses one, two, three, four and five will be sent out by transmitter 138. This pro-

duces the shift from upper to lower case at the printer.

The bar 141 extends through the end plate 70 (Figs. 3 and 7). This projection has a hump 148 between two notches 149 and 150 in which is seated a roller 151. This roller is seated in notch 149 when the bar 141 is at the right in Fig. 14 and is in position for transmitting lower case characters and in notch 150 for transmitting upper case characters. As the bar 141 shifts from one position to the other, the roller 151 passes over the hump 148 and rotates the arm 151' to which it is fastened. This movement rotates shaft 152 and arm 153 against tension of spring 154, the spring being fastened to an arm 154' on shaft 152 (Fig. 3). During this movement the switch lever 155 is released from engagement with the catch on arm 153, which opens the switch 156 in circuit with magnet 157. Magnet 157 has switch tongues 158, 159 (Fig. 12) engaging contacts 160, 161, respectively, in the other position.

It was previously stated, in describing the raising and lowering of the rack 13' of the Creed selector head, that an extension 39 was fastened to arm 38. This extension ends in an upwardly extending post in position to be engaged by armature 163' (Fig. 1) when magnet 163'' is energized. When the magnet 163'' is energized arm 39 is forced downwards and held so that the roller 35 cannot follow the surface of cam 36. This disables the tape feeding arrangement by maintaining the rack out of engagement with the gear 32 during the shift cycle. This magnet is energized by closure of contacts 158 and 160 and also by a contact 164 in parallel therewith. Switch 164 is closed momentarily once during each revolution of shaft 124 by engagement of the cam hump 165 with the switch arm 166 (Figs. 2 and 12).

The operation of the code converter is as follows assuming the letters A and B are being sent in this order:

Let it be supposed that the tape 14 is in position in the Creed head so that the first feed hole 167 (Figs. 10 and 13) is midway between the last two pairs of pecker bars 16, 17, namely, the two shown in Fig. 10. There are ten of these pairs of pecker bars but only seven of them are utilized in the embodiment disclosed. This means that the pecker bars for the first seven feed holes, whenever selected, will operate the selector bars 55 by engaging the levers 45 with levers 48. At about this time cam 53 permits spring 52 to force selector levers 45 to the left in Fig. 10.

By inspecting Fig. 13 it will be seen that, counting from the rear in Fig. 10, the first, fourth, eighth, ninth, eleventh and thirteenth selector bars will be moved to the right by this action. As will be evident from Fig. 10, movement of bars 1 and 4 will align the slots under the first lever 66 which is for the letter A. The selector bars are so slotted (see Fig. 11) that the movement of the other bars mentioned does not interfere with the desired selection. Lever 66 for the letter A will not immediately drop, as it is held in raised position by cross bar 109. Shortly after the slots are aligned cams 108 will permit the operating ball of which cross bar 109 is a part, to lower and cross arm 66 for letter A will immediately drop into the slot, Fig. 8. This takes place just before the cam follower 116 snaps off of the abutment of cam 115 (Figs. 3 and 8).

When the cam follower 116 rode up on the surface of cam 115 the mis-selection bar 97 was 75

5 moved to the right in Fig. 8, or to the left in Fig. 11, and this removed the teeth or ridges normally positioned under the cross bar 66 for code character A and the cross bars 66 for all of the other characters except cross bar 66a, for the mis-selection character. Under the latter cross bar, the movement of the mis-selection bar, as referred to, placed a ridge. Since the supporting bar or ball 109 drops away from the cross levers 66 10 before follower 116 leaves cam 115, the cross bar for letter A dropped into its slot. Immediately thereafter the cam follower left cam 115 but mis-selection bar 97 cannot move to the left under tension of its spring because the cross bar for 15 letter A is in a slot and stops such movement.

Let it be supposed that the character previous to letter A was an upper case character. This means that shift bar 88 will be up and shift bar 87 down, Fig. 14. When cross lever 66 for the 20 letter A dropped into the slots in the cable code bars 55, shift bar 88 was engaged and forced downwards. This moved catch 153 from under the operating arm 155 and opened switch contact 156 (Fig. 7) which had been previously closed 25 when operating ball 109 raised the adjustable, eccentric projection 168 fastened to the arm 110 of the operating bail. The shifting of the bar 141 when bar 88 was engaged, also moved locking lever 133 from engagement with the bell crank 30 lever 130 of shift transmitter 138. This placed the third switch cam in operative position on transmitter 138 and a signal consisting of all five pulses is transmitted to the printer which 35 will shift the printer platen in a well known way for printing lower case.

The opening of contact 156 de-energized magnet 157 and interrupted the circuit of Baudot signal transmitter 126 at contact 161. This disabled the Baudot signal transmitter for one revolution while the shift signal is going out over the line. It also opened its holding circuit at switch 160. The closure of switch 162 by de-energization of magnet 157 energized magnet 163" and stopped the tape feed. Closure of switch 163 closes the circuit of shift transmitter 138 so that the shift signal of the first, second, 40 fourth and fifth pulses can be transmitted. Immediately after the fifth pulse of the shift signal is transmitted cam 165 on the shift transmitter shaft 124 (Fig. 2) closes switch 164 and re-energizes magnet 157. The circuit of shift transmitter 138 is interrupted and the circuit of signal transmitter 126 is closed, switch 156 having been previously closed by projection 168 on the operating ball 109.

When cross bar 66 for the letter A descended under tension of its spring into the slot of the cable code selector bars, Baudot code bars 83, 84, were depressed. This removed the locking levers 133 from the fourth and fifth bell crank levers 130 of signal transmitter 126.

The first described rotation of shafts 124 and 125 was devoted to the sending out of the shift signal, Baudot transmitter 126 and the cable code tape feed being disabled. In the next rotation transmitter 126 is in circuit and shift transmitter 138 is out of circuit. Consequently the moving of the fourth and fifth locking levers closed the fourth and fifth switch contacts 131 50 as shaft 125 rotated. This sent out pulses for the fourth and fifth positions in the revolution just as though the key for the letter A had been depressed on the usual teletypewriter transmitter. This printed the letter A at the receiver.

75 The deenergization of magnet 163" in the shift

operation permitted the roller 35 of the rack feed to engage cam 36 and the rack 13' to re-engage gear 32. On the movement of arm 24 to the left in Fig. 10 the rack is returned until it engages the projection 42 corresponding to the feed space hole 169. Projection 42 was not moved because its associated pecker pins did not rise in the previous operation, there being no code perforations punched in the tape at this point.

On the movement of the arm 24 to the right 10 the rack rotates the gear 32 and moves the tape so that feed hole 170 is directly between the first pair of pecker bars, namely, the two shown in Fig. 10. This will move the cable code selector bars 55 so that the cross lever 66 for the letter 15 B will fall into the slots as soon as the bail 109 is dropped downward by the cam mechanism. Since the previous code character A was a lower case character the shift bars will be in the position shown in Fig. 14. Consequently, when the cross 20 bar 66 for the letter B drops there will be no movement of bar 141 and no opening of the switch 156 (Fig. 7), thus magnet 157 will remain energized and the signal transmitter 126 will send out the pulses for the letter B by lowering of Baudot 25 code bars 80, 81 and 84, which will cause pulses to be sent out by the first, fourth and fifth switches in the teletype transmitter. This will print the letter B at the receiver.

If an upper case code character should be the 30 next one on the tape for transmission it would engage bar 87 and force cross bar 141 to the left (Fig. 14). As the shift roller 149 passed the hump 148 it would open switch 156 in a way previously described and would transmit the shift signal 35 through transmitter 138, interrupt the transmission of a signal by transmitter 126 and lock the feed rack to stop the movement of the perforated tape. As before, this will take up the time of one revolution of the transmitter shafts 124 and 125. 40 On the next revolution the signal would be sent out for the code character which would print an upper case character at the printer because the shift signal of the first, second, fourth and fifth pulses would have shifted the platen of the printer 45 to the upper case position.

If it should happen that the selector bars are not moved to present an aligned slot to the cross levers 66, mis-selection bar 97 would move back to the left in Fig. 8 as soon as cam follower 116 50 leaves cam 115. This will present a slot to cross lever 66a. It will drop down and depress the third Baudot code bars (Fig. 11). Locking lever 133 will be released and transmitter 126 will send out the third pulse. This will cause the printer 55 to print the mis-selection character which, by way of example, has been given as a Maltese cross. If a lower case code character had been previously sent, depression of bar 87 would delay the printing one revolution while the shift signal is 60 being transmitted, as already described.

It will be seen that my invention provides for the automatic conversion of cable code signals into Baudot signals. As previously stated, if it is desired to use all of the cable code characters one 65 could merely expand my converter to have sufficient levers and cable code selectors to accomplish this result and my invention is intended to provide for such an arrangement.

It will be apparent that one may use only one 70 cam 108 for operating the cross bail 109 and that various other changes may be made. The detail construction disclosed has been merely for presenting a complete operative structure and changes may be made in the various parts with- 75

out in any way departing from the spirit of the invention.

Having described my invention, what I claim is:

5 1. In electric telegraphy, means for storing signals in a single group of code characters, each code character being different from the others, a transmitter having means for sending signals in two code groups, a code character in one group being identical with one code character in the 10 other group and means operated by said signal storing means for causing said transmitter to send said stored signals in accordance with said two code groups.

15 2. In electric telegraphy, means for storing signals in a single group of code characters, each code character being different from the others, a transmitter having means for sending signals in two code groups, a code character in one group being identical with one code character in the 20 other group, additional means for transmission of a shift signal before transmitting a code character in one group after transmission of a preceding code character in the other group and means operated by said signal storing means for causing said transmitter to send the stored signals and 25 additional means to send said stored signals in accordance with said two code groups.

30 3. In electric telegraphy, a perforated tape containing stored signals in single case only, a transmitter having means to send said code characters in double case and having additional means for sending a shift signal when a transmitted code character of one case is followed by a code character of the other case and 35 means operated by said tape for causing said transmitter to send the signals stored thereon by transmission of the double case and shift code signals.

40 4. In electric telegraphs, a perforated tape containing a message in code characters of unequal length, a transmitter having means for sending code characters of equal length in upper and lower case and for sending shift signals upon changing from one case to the other and means 45 operated by said tape for causing said transmitter to send said message in code characters of equal length.

50 5. In electric telegraphs, means for storing a message in code characters of unequal length, a transmitter having means for sending code characters of equal length in upper and lower case and for sending shift signals upon changing from one case to the other and means operated by said first mentioned means for causing said transmitter to send said message in code characters of equal length.

60 6. In electric telegraphs, a transmitter having means to selectively transmit upper and lower case code characters, a transmitter having means to transmit upper and lower case shift signals, a perforated tape having a message stored thereon in single case code characters, means operated by said tape to cause the first transmitter to transmit the said message in double case code 65 characters and means for delaying the transmission of a code character by the first transmitter when it has a different case from the preceding code character and for causing the second transmitter to transmit a shift signal, during such delay, indicating said different case.

70 7. In electric telegraphs, a signal circuit, a transmitter having means to selectively transmit upper and lower case code characters, each character having the same time period, a transmitter having means to transmit upper and lower case

shift signals over said circuit, a perforated tape having a message stored thereon in single case code characters, means operated by said tape to cause the first transmitter to transmit the said message in double case code characters over said 5 circuit and means for disconnecting the first transmitter from said circuit when a code character has a different case from the preceding code character and for connecting the second transmitter to said circuit for transmission of a 10 shift signal indicating said different case, and means for disconnecting the second transmitter from said circuit and connecting the first transmitter thereto when the said shift signal has been transmitted.

15 8. In electric telegraphs, a signal circuit, a transmitter having means to selectively transmit upper and lower case code characters over said circuit, a transmitter having means to transmit upper and lower case shift signals over said 20 circuit, a perforated tape having a message stored thereon in single case code characters, means operated by said tape to cause the first transmitter to transmit the said message in upper and lower case code characters over said circuit and 25 means for disconnecting the first transmitter from said circuit when a code character has a different case from the preceding code character and for connecting the said transmitter to said circuit for transmission of a shift signal indicating 30 said different case.

35 9. In apparatus for sending equal length code signals in double case, a signal circuit, a plurality of cams, switches in said circuit, arms operated by said cams for operating the switches, locking 40 levers for preventing operation of the arms by said cams, a shift-signal transmitter, a tape having perforations representing unequal length code characters in single case, a plurality of selector bars for operating said locking levers to 45 permit the cams to operate said arms, a code lever for each of the code characters extending transversely of the selector bars, a plurality of slotted selector bars, means operated by said tape for moving the slotted selector bars to present 50 aligned slots under the code lever for the code character being transmitted from said tape, means to move a code lever into the aligned slots to depress certain of the first mentioned bars, an additional switch in said signal circuit and 55 means operated by said code lever for operating said additional switch when the previously transmitted code character was of different case therefrom.

10. In apparatus for sending equal length code 55 signals in double case, a signal circuit, a plurality of cams, switches in said circuit, arms operated by said cams for operating the switches sending said signals, locking levers for preventing operation of the arms by said cams, a shift signal 60 transmitter, a tape having perforations representing unequal length code characters in single case, a plurality of selector bars for operating said locking levers to permit the cams to operate said arms, a code lever for each of the code characters extending transversely of the selector bars, a plurality of slotted selector bars, means operated 65 by said tape for moving the slotted selector bars to present aligned slots under the code lever for the code character being transmitted from 70 said tape, means to move a code lever into the aligned slots to depress certain of the first mentioned bars, an additional switch in said signal circuit and means operated by said code lever for operating said additional switch when the 75

previously transmitted code character was of different case therefrom, and to connect the said shift signal transmitter to the signal circuit.

11. In apparatus for sending equal length code signals in double case, a signal circuit, a first and second transmitter each having five signal cams and switches in said circuit, arms operated by said cams for operating the switches, five locking levers for preventing operation of the arms by cams of first transmitter, and a single locking lever for preventing operation of one arm only, by a cam of the second transmitter, a tape having perforations representing unequal length code characters in single case, a plurality of selector bars for selectively operating the five levers of the first transmitter to permit the cams to operate their arms for operating the switches, a code lever for each of the code characters extending transversely of the selector bars, a plurality of slotted selector bars, means operated by said tape for moving the last mentioned selector bars to present aligned slots under the code lever for the code character being transmitted from said tape, means to move the code lever into the aligned slots to depress certain of the first mentioned bars, an additional switch connecting the first transmitter to said signal circuit and means operated by said code lever for opening said additional switch when the previously transmitted code character was of different case therefrom, connecting the second transmitter to the signal circuit and operating the single locking lever of said second transmitter.

12. In electrical telegraphy, a perforated tape for storing signals in a single group of code characters, each code character being different from the others, a transmitter having means for sending signals in two groups of code characters, a code character in one group being identical with a code character in the other group, means operated by said tape for causing said transmitter to send signals stored thereon in accordance with said two code groups and means to cause said transmitter to transmit a mis-selection signal when the last mentioned means fails to operate.

13. In electrical telegraphy, a perforated tape for storing signals in a single group of code characters, each code character being different from the others, a transmitter having means for sending signals in two groups of code characters, a code character in one group being identical with a code character in the other group, means operated by said tape for causing said transmitter to send signals stored thereon in accordance with said two code groups and means to cause said transmitter to transmit a mis-selection signal when the last mentioned means fails to operate, and means to cause the mis-selection lever to enter the aligned slots and depress certain of the first mentioned selector bars.

14. In apparatus for sending equal length code signals in double case, a signal circuit, a plurality of cams, switches in said circuit operated by said cams for sending said signals, locking levers for preventing operation of the switches by said cams, a shift-signal transmitter, a tape having perforations representing unequal length code characters in single case, a plurality of selector bars for operating said operating levers to permit the cams to operate said switches, a code lever for each of the code characters, including a mis-selection character, extending transversely of the selector bars, a second plurality of slotted selector bars, means operated by said tape for moving the last mentioned selector bars to present an

aligned slot under the code lever for the code character being transmitted from said tape, means to move a code lever into the aligned slots to depress certain of the first mentioned bars, and means to align the slots in the last mentioned selector bars under the mis-selection code lever when none of the other code levers move into the slots aligned thereunder.

15. In apparatus for changing single case into double case code, a tape having perforations representing single case code characters, seeker pins positioned adjacent said tape, selector bars having a plurality of slots, a plurality of upper and lower case code levers extending across the selector bars, means operated by the seeker pins for moving the selector bars to align slots with one of the levers for each single case code character when the tape perforations therefor are in operating position, a shaft signal switch, operating means for the switch, and means to disconnect the operating code lever from said operating means when the previous operation was by a code lever of the same case and to connect it thereto when it was by a code lever of different case.

16. In apparatus for changing single case into double case code, a tape having perforations representing single case code characters, seeker pins positioned adjacent said tape, selector bars having a plurality of slots, a plurality of upper and lower case code levers extending across the selector bars, means operated by the seeker pins for moving the selector bars to align slots with one of the levers for each single case code character when the tape perforations therefor are in operating position, a pair of shift bars, one extending across the lower case code levers and the other across the upper case code levers, and means for sending a shift signal when either one of said shift bars is operated by a code lever.

17. In apparatus for changing single case into double case code, a tape having perforations representing single case code characters, seeker pins positioned adjacent said tape, selector bars having a plurality of slots, a plurality of upper and lower case code levers extending across the selector bars, means operated by the seeker pins for moving the selector bars to align slots with one of the levers for each code character when the tape perforations therefor are in operating position, a pair of shift bars, one extending across the lower case code levers and the other across the upper case code levers, a transmitter for sending pulses in double case code, means operated by each of said levers for causing the transmitter to send pulses representing the code characters of the respective levers, and means operated by said shift bars for opening the circuit of said transmitter and sending a shift signal.

18. In apparatus for changing single case into double case code, a tape having perforations representing single case code characters, seeker pins positioned adjacent said tape, selector bars having a plurality of slots, a plurality of upper and lower case code levers extending across the selector bars, means operated by the seeker pins for moving the selector bars to align slots with one of the levers for each single case code character when the tape perforations therefor are in operating position, a shift signal switch, operating means for the switch, means to disconnect the operating code lever from said operating means when the previous operation was by a code lever of the same case, and to connect it thereto when it was by a code lever of different case, a signal transmitter for sending pulses in double case

code, and means operated by each of said levers for causing the signal transmitter to immediately start the sending of pulses representing the code characters of the respective levers when the operating lever is disconnected from said operating means and to delay the sending of said pulses when it is connected thereto.

19. In apparatus for changing single case into double case code, a tape having perforations representing single case code characters, seeker pins positioned adjacent said tape, selector bars having a plurality of slots, a plurality of upper and lower case code levers extending across the selector bars, means operated by the seeker pins 5 for moving the selector bars to align slots with one of the levers for each single case code character when the tape perforations therefor are in operating position, a shift signal switch, operating means for the switch, means to disconnect 10 the operating code lever from said operating means when the previous operation was by a code lever of the same case and to connect it thereto when it was by a code lever of different case, a signal transmitter for sending pulses in double case code, a shift signal transmitter, and means 15 operated by each of said levers for causing the signal transmitter to immediately start the sending of pulses representing the code characters of the respective levers when the operating code lever is disconnected from said operating means and to cause the shift transmitter to send a shift signal when it is connected thereto, and means 20 to disable the tape feeding means while the operating code lever is connected to said operating means.

20. In apparatus for changing single case into double case code, a tape having perforations representing single case code characters, means for feeding the tape, seeker pins positioned adjacent said tape, selector bars having a plurality of slots, a plurality of upper and lower case code 25 levers extending across the selector bars, means operated by the seeker pins for moving the selector bars to align slots with one of the levers for each single case code character when the tape perforations therefor are in operating position, a shift signal switch, operating means for said 30 switch, means to disconnect the operating code lever from said operating means when the previous operation was by a code lever of the same case and to connect it thereto when it was by a code lever of different case, and means for disabling the tape feeding means while the operating code lever is connected to said operating means.

21. In apparatus for changing single case into double case code, a tape having perforations representing single case code characters, means for feeding the tape, seeker pins positioned adjacent said tape, selector bars having a plurality of slots, a plurality of upper and lower case code 35 levers extending across the selector bars, means operated by the seeker pins for moving the se-

lector bars to align slots with one of the levers for each single case code character when the tape perforations therefor are in operating position, a shift signal switch, operating means for said switch, means to disconnect the operating 5 code lever from said operating means when the previous operation was by a code lever of the same case and to connect it thereto when it was by a code lever of different case, a signal transmitter for sending pulses in double case code, a shift signal transmitter, means operated by each 10 of said levers for causing the signal transmitter to send pulses representing the code characters of the respective levers when the operating lever is disconnected from said operating means and to cause the shift transmitter to send a shift signal when it is connected thereto, and means to disable the tape feeding means while the operating code lever is connected to said operating 15 means.

22. In apparatus for changing single case into double case code, a tape having perforations representing single case code characters, means for feeding the tape, seeker pins positioned adjacent said tape, selector bars having a plurality 20 of slots, a plurality of upper and lower case code levers extending across the selector bars, means operated by the seeker pins for moving the selector bars to align slots with one of the levers for each single case code character when the tape perforations therefor are in operating position, a pair of shift bars, one extending across the lower case code levers and the other across the upper case code levers, means for sending a shift signal when either one of said shift bars is 25 operated by a code lever, and means for disabling the tape feeding means while the shift signal is being sent.

23. In apparatus for changing single case into double case code, a tape having perforations representing single case code characters, means for feeding the tape, seeker pins positioned adjacent said tape, selector bars having a plurality of slots, a plurality of upper and lower case code 30 levers extending across the selector bars, means operated by the seeker pins for moving the selector bars to align slots with one of the levers for each code character when the tape perforations therefor are in operating position, a pair of shift bars, one extending across the lower case 35 code levers and the other across the upper case code levers, a transmitter for sending pulses in double case code, means operated by each of said levers for causing the transmitter to send pulses representing the code characters of the respective levers, means operated by said shift bars for opening the circuit of said transmitter and sending a shift signal, and means for disabling the tape feeding means while the shift signal is being sent.

JAMES A. SPENCER.
